UNITED STATES PATENT OFFICE.

CHARLES J. BRITT, OF WILLINGTON, SOUTH CAROLINA.

TRACTOR.

1,341,537.

Specification of Letters Patent.

Patented May 25, 1920.

Original application filed April 15, 1918, Serial No. 228,709. Divided and this application filed November 25, 1919. Serial No. 340,602.

To all whom it may concern:

Be it known that I, CHARLES J. BRITT, a citizen of the United States, residing at Willington, in the county of McCormick 5 and State of South Carolina; have invented new and useful Improvements in Tractors, of which the following is a specification.

This application is a division of my temporary application filed April 15, 1918, 10 Serial No. 228,709, which has eventuated into Patent 1,330,733 dated February 10, 1920.

One object of the present invention is to produce a simple and improved construction 15 whereby, in steering, the large driven ground wheel will be tilted in the direction in which the machine is to be driven.

Another object of the present invention is to produce a simple and improved steering 20 gear whereby a pair of steering wheels will be actuated simultaneously with the tilting parts of the invention.

With these and other ends in view which will appear as the nature of the invention 25 is better understood, the same consists in the improved construction, arrangement and combination of parts which will be herein-after fully described and particularly pointed out in the claims.

30 In the accompanying drawing has been illustrated a simple and preferred form of the invention, it being, however, understood that no limitation is necessarily made to the precise structural details therein exhibited, 35 but that changes, alterations and modifications within the scope of the claims may be resorted to when desired.

In the drawings:

Figure 1 is a top plan view of a tractor 40 constructed in accordance with the invention.

Fig. 2 is a side elevation of the tractor.

Fig. 3 is a rear elevation.

Fig. 4 is a sectional detail view taken on 45 the line 4-4 in Fig. 3.

Fig. 5 is a horizontal detail view taken on the line 5-5 in Fig. 3.

Corresponding parts in the several figures are denoted by like characters of reference.

50 The frame of the machine, which may be constructed of channel steel or other appropriate material, includes the side members 15 and the front and rear cross-bars 16, 17. The side members 15 are provided inter-

55 mediate the ends thereof with downwardly

offset portions 18 adapted to support a motor which is conventionally indicated by M.

The ground-engaging driving wheel A is driven from the axle 27, said axle being shown as being provided at the ends thereof with spur wheels 28 receiving power from the motor M, it being of course understood that any convenient well known means may be used for transmitting power from the motor to the axle.

60 The rear axle 36' of the improved machine is equipped with steering wheels 37, 38 of the ordinary automobile type, said steering wheels being supported by the steering knuckles 39, each having an arm 40; said arms being connected together by a rod or link bar 41. The wheel 38 is preferably of larger diameter than the wheel 37, and the rear axle will thus occupy a slightly tilted position which, however, does not interfere 65 with the use of the tractor for general purposes.

70 Supported on the rear axle by brackets or supporting members 42, is a transversely inclined bolster 43 with the high side of which one side member 15 of the main frame is connected by a hinge 44. The frame of the machine supports a vertical steering shaft 45 having a hand wheel 46, said shaft being connected by a universal joint 47 with another approximately vertical shaft 48, the latter being supported for rotation in brackets or bearing members associated with the rear axle 36 and supported on the latter. The steering shaft is capable of sliding longitudinally in its bearings in the frame of 75 the machine. The shaft 48 carries a worm 49 meshing with a worm gear 50 on a shaft 51 which is supported for rotation in a bearing lug 52 connected with the machine 80 frame. The shaft 51 also carries a pinion 53 meshing with an arcuate rack 54 rising from and connected with the rear axle. Said rack is preferably guided through a slot 54' in the bolster 43, as clearly seen in Fig. 2. The 85 worm shaft 48 carries a pinion 55 meshing with a spur wheel 56 on a shaft 57, said shaft carrying also a pinion 58 that meshes with a rack 59 at one end of a bar 60, the other end of which is pivotally connected at 90 61 with the arm 40 that extends from one of the steering knuckles 39. A thrust roller 62 serves to keep the rack 59 of the bar 60 in constant engagement with the pinion 58.

95 Radius rods 63, 64 are connected with the 100

axle 36' adjacent to the wheels 37 and 38, respectively, the forward ends of said radius rods being connected with one of the side members 15 of the frame structure by a ball 5 and socket joint 65.

From the foregoing description taken in connection with the drawings hereto annexed, the operation and advantages of the improved tractor will be readily understood 10 by those skilled in the art to which it appertains. A three-wheel tractor is peculiarly adapted to travel over uneven ground, owing to the fact that the ground is engaged only at three points, thereby insuring stability and avoiding undue shaking and vibration. In steering the machine, the steering wheels 37, 38 will not only be turned in the proper direction by the action of the steering shaft, but at the same time the 15 frame of the machine will be tilted with respect to the rear axle, thereby tilting the driving wheel A in the direction in which the turn is to be made, thereby greatly facilitating the turning of sharp corners. 20 This tilting of the frame and the driving wheel, it will be observed, is effected simultaneously with the adjustment of the steering wheels and by mechanism actuated by the steering shaft. When the frame is 25 tilted, the bearings of the steering shaft will slide longitudinally of the latter, and the presence of the universal joint 47 will permit the necessary movement to take place without straining or breaking any of the 30 parts of the device. The general construction of the improved tractor is simple and inexpensive, and it will be found to be thoroughly useful for a variety of purposes. It may here be mentioned that draft bars 35 indicated at 70 have been shown connected with the ends of the axle 27, said draft bars extending downwardly and rearwardly and being supported by braces 71 connected with the side members of the frame. The draft 40 bars may be connected together by a hitching bar 72 with which plows or other implements may be connected. It is obvious, however, that no limitation is intended as to the manner of utilizing the tractor or the manner 45 of connecting it with implements or vehicles to be drawn or operated thereby.

By arranging the bolster 43 in an inclined position as shown and connecting the main frame hingedly with the high side of the 50 bolster, the frame may obviously be dipped or tilted either to the right or to the left, without interference by the bolster.

Manifestly the frame of my tractor can be extended rearwardly, say five feet, to 55 permit of the use of a back radius rod, without affecting my invention.

Having described my invention, what I claim and desire to secure by Letters-Patent, is:

65 1. In a three-wheel tractor, a main frame,

a single longitudinal-central driving wheel, means for supporting the driving wheel for rotation with respect to the main frame, means for rotating the driving wheel, steering wheels and steering means including 70 means for tilting the frame to tilt the driving wheel in the direction in which a turn is to be made.

2. In a three-wheel tractor, a main frame, a longitudinal central main driving wheel, 75 and means for tilting the frame and the driving wheel in concert.

3. In a three-wheel tractor, a main frame, a main driving wheel, an axle having steering wheels, means for supporting the main 80 frame with respect to the axle, said means including a hinge connection between the supporting means and one side member of the main frame, and steering means including means for tilting the main frame and 85 the main driving wheel.

4. In a three-wheel tractor, a main frame having side members, an axle extending through said side members, a main driving wheel carried by said axle, means for rotating 90 said axle, means for rotating said wheel, an axle having steering wheels, a bolster supported by said axle, a hinge connection between the bolster and one side member of the frame, and means for tilting the main 95 frame with respect to the bolster.

5. In a three-wheel tractor, a main frame having side members, an axle extending through said side members, a main driving wheel carried by said axle, means for rotating 100 said axle, means for rotating said wheel, an axle having steering wheels, a bolster supported by said axle, a hinge connection between the bolster and one side member of the frame, and means for tilting the main 105 frame with respect to the bolster, means including an arcuate rack supported by the axle that carries the steering wheels, a shaft carried by the main frame and having a pinion engaging said rack, and means for 110 rotating the shaft.

6. In a three-wheel tractor, a main frame having side members, an axle extending through said side members, a main driving wheel carried by the axle, means for effecting 115 rotation of said main driving wheel to propel the tractor, a secondary axle having steering wheels, a bolster supported by said secondary axle, a hinge connection between said bolster and one side member of the 120 main frame, and means for simultaneously tilting the main frame and effecting adjustment of the steering wheels to steer the tractor.

7. In a three-wheel tractor, a main frame 125 having side members, an axle extending through said side members, a main driving wheel carried by the axle, means for effecting rotation of said main driving wheel to propel the tractor, a secondary axle having 130

steering wheels, a bolster supported by said secondary axle, a hinge connection between said bolster and one side member of the main frame, and means for simultaneously 5 tilting the main frame and effecting adjustment of the steering wheels to steer the tractor, said steering wheels being of unequal diameter.

8. In a three-wheel tractor, a main frame 10 having side members, an axle extending through said side members, a main driving wheel carried by the axle, means for rotating the driving wheel to propel the tractor, a secondary axle, knuckles and steering 15 wheels carried by said secondary axle, said knuckles having radial arms, a link bar connecting said arms, a rack bar connected with one of the arms, a pinion meshing with the rack bar, means for rotating the pinion including a shaft having a worm, a steering 20 shaft rotatably and slidably supported in the main frame, a universal joint connection between the steering shaft and the worm-carrying shaft, a shaft supported for rotation by the main frame, a worm gear car-

ried by said shaft and meshing with the worm, a pinion also carried by said shaft and an arcuate rack supported stationary with respect to the secondary axle and meshing with the pinion whereby adjustment of 30 the steering wheels and tilting adjustment of the main frame may be simultaneously effected by means of the steering shaft.

9. In a three-wheel tractor, a main frame 35 having side members, an axle extending through said side members, a single driving wheel carried by said shaft intermediate the side members, and means for rotating the driving wheel to propel the tractor, a secondary axle having steering wheels, a bolster 40 supported by said axle, a hinge connection between said bolster and one side member of the main frame, radius rods extending from the secondary axle to the side member of the frame having hinge connection with 45 the bolster, and a ball and socket joint connection between the radius rods and said side member.

In testimony whereof I affix my signature.
CHARLES J. BRITT.
